UNITED STATES PATENT OFFICE.

FRED L. MACKENZIE, OF BEVERLY, MASSACHUSETTS, ASSIGNOR TO UNITED SHOE MACHINERY CORPORATION, OF PATERSON, NEW JERSEY, A CORPORATION OF NEW JERSEY.

CONTROLLING MECHANISM.

Application filed February 20, 1922. Serial No. 537,870.

This invention relates to fastening inserting machines such, for example, as are employed in the manufacture of shoes, and particularly to improvements in the mechanism 5 by which the operation of such machines is controlled.

This invention is particularly applicable to step-by-step machines provided with fastening-inserting instrumentalities arranged 10 to insert fastenings successively in the work and to feed the work between the insertion of successive fastenings. The invention is illustrated as embodied in a machine designed to insert loose nails, though evidently 15 it is not limited to use in connection with the insertion of that kind of fastenings.

Such machines are commonly provided with clutch mechanism by means of which the operation of the fastening-inserting instrumentalities may be initiated and suspended. A work support also is commonly provided upon which the work is held during the insertion of fastenings. Means is also ordinarily provided for lowering the 20 work support to facilitate the removal of the work therefrom when the machine is stopped and for raising it after a new piece of work has been positioned thereon before or as the machine is again started. This work support is caused to press the work with considerable force against an abutment or presser plate on the machine, and means is provided for relieving this pressure during the 25 feeding movement of the work. Such machines for many years were constructed with separate treadles to control the raising and lowering of the work support and the starting and stopping of the fastening-inserting and work-feeding instrumentalities. Later 30 on machines of this type were built provided with a single treadle connected to the work support and the clutch mechanism in such a manner that an operative, by depressing the treadle, first raised the work support from work-receiving to work-presenting position and then, by a continued movement of the treadle, operated the clutch to start the machine. This development was a marked step 35 in advance since it facilitated and speeded up the operation of the machine, at the same time reducing the foot work required of the operator in depressing and releasing the treadle. It was still necessary, however, for

the operator to lift the work support by his own bodily strength each time the machine 55 was started as well as to compress various springs so as to store energy utilized to control various parts during the stopping of the machine.

Machines of this type operate at a comparatively high speed, ordinarily from three hundred to four hundred or more revolutions per minute. It has not proved practical to embody in these high-speed machines controlling mechanism of the nature used in certain low-speed gang machines, for example heel-attaching machines, in which power supplied through the clutch which operates the fastening-inserting instrumentalities is also utilized to raise the work support before 60 the insertion of the fastenings. The high-speed, step-by-step machines of the type in question are provided with a number of cams or other power-transmitting devices arranged to time the motions of various parts of the machine with a high degree of accuracy in each cycle of operation. If it were attempted to raise the work support by power supplied through the clutch, it would necessitate either slowing down the machine 65 or crowding together the other movements of the machine in a manner which would render exceedingly difficult, if not absolutely impractical, the proper timing of the different motions to be given the parts of the machine in each cycle of operation.

The present invention obviates this difficulty by providing power-operated means for raising the work support which operates prior to the throwing in of the clutch of the machine and therefore does not interfere at all with the timing of the motions of the parts of the machine which receive their power through the clutch.

This is accomplished in the herein-described embodiment of the invention by an organization in which power-operated means is utilized to raise the work support when the machine is started and subsequently but almost simultaneously to throw in the clutch which supplies power to the fastening-inserting and work-feeding instrumentalities, thus reducing to a large extent the force which the operative must apply to the treadle of the machine and minimizing the tiring effect of the machine upon the operative.

Such mechanism permits the use of a treadle having a very short throw so that the operative may depress and release it with the forepart of his foot without moving his heel 6 from the floor, the treadle being at the same time so arranged that it may be depressed through this short distance by a minimum of force. Conversely when the fastening inserting operation has been completed, the release 10 of the treadle permits the throwing out of the clutch and the subsequent lowering of the work support under the control of mechanism provided for that purpose. Thus the effort necessary for operating a machine 15 of this type is very greatly reduced as compared with that heretofore necessary.

Preferably and as shown the power-operated means is under the control of the operative who can at any time cause that means 20 to become operative to raise the work support and throw in the clutch. The controlling means, however, when actuated will respond and initiate the operation of the machine only when the work support has been 25 raised to its operative position. Similarly the treadle may be released at any time to halt the insertion of fastenings. The effect of the release of the treadle will, however, be suspended until a predetermined point in 30 the cycle of operations, in the case of the illustrated machine until the completion of the insertion of the fastening inserted during the cycle in which the treadle is released; then the clutch will be thrown out and the work 35 support immediately lowered. Thus when the machine is started the clutch is thrown in substantially as the work support reaches its raised position and when the machine is stopped the work support starts down just 40 as the clutch is thrown out.

When the connections have been moved to elevate the work support and throw in the clutch, they must be maintained in such position during the continued operation of the machine. Also the work support is preferably lowered when the operation of the machine is suspended by the throwing out of the clutch. To this end, means are provided 45 operatively associated with such connections 50 for retaining the work support in raised position and the clutch thrown in and also for rendering the retaining means inoperative on said connections so as to stop the operation of the machine and lower the work support. 55

The invention further contemplates the provision of novel means for elevating the work support, aside from and without reference to the means employed to effect engagement and disengagement of the clutch to start and stop the machine. In this aspect the invention contemplates the provision of a member movably mounted on the frame of the machine and operated by a constantly

moving shaft and mechanism connected to 65 the work support and comprising an element positioned normally out of the path of movement of said member but arranged for interposition into the path of movement of the member to cause the work support to be 70 raised.

In accordance with another feature of the invention retaining means is provided to maintain the work support in the position to which it is raised by the power-operated 75 means, and the work support is released from the control of the retaining means by means operated by the clutch operating mechanism which controls the operation of the machine thereby permitting the work support to be 80 lowered. As illustrated, the clutch comprises a clutch member moved out of clutching engagement by the power of the machine at a predetermined time in the cycle of operations 85 of the machine and controlled by means having connections to the work support controlling means, such connections having means co-acting therewith for maintaining the work support in raised position and arranged to be rendered inoperative on said connections by 90 means operated by the clutch member moving means so that the work support is lowered substantially simultaneously with the stopping of the machine.

This application is a continuation in part 95 of my application for fastening inserting machines having Serial No. 260,999, filed Nov. 4, 1918, and renewed Jan. 3, 1921, under Serial No. 434,843, as to all subject-matter common to the two.

The invention will be herein illustrated and described in its application to a machine of the type disclosed in Letters Patent of the United States No. 1,030,775, granted June 25, 1912, on an application of George 105 Goddu, for inserting previously formed fastenings, such as loose nails, the machine having incorporated therein controlling mechanism substantially as disclosed by Letters Patent of the United States No. 1,011,941, 110 granted Dec. 19, 1911, on another application of said Goddu. It is realized however that the use of the invention is not limited thereto, and that it may be employed in other relations including embodiment in fastening 115 inserting machines of other types. Moreover, the mechanism herein set forth as a preferred exemplification of the invention may be considerably modified without departing from the principles thereof. The 120 scope of the invention is therefore to be limited only as required by the appended claims.

With the above and other objects and features in view the invention will now be described in connection with the accompanying 125 drawings and pointed out in the subjoined claims.

Fig. 1 is a side elevation of the base por-

tion of a fastening inserting machine embodying the present invention;

Figs. 2, 3 and 4 are vertical sectional views showing different positions of the power-operated mechanism by which the clutch and work support are operated and of the controlling means therefor;

Fig. 5 is a side elevation partly in section of the clutch operating mechanism; and
10 Fig. 6 is a front view of the fastening inserting instrumentalities carried by the head of the machine.

The illustrated machine is provided with a raceway 2 (Fig. 6) to which fastenings 15 may be supplied in any usual manner and by which they are conducted to fastening inserting instrumentalities including a throat member 4, a work penetrating and feeding awl 6, and a driver 8 which may be operated, 20 for example, as disclosed in the previously referred to Letters Patent of the United States No. 1,030,775. A suitable work support such as a horn 10 carried by a horn post 12 (Fig. 1) is provided to hold the work in 25 operative relation to the fastening inserting means. The machine is governed in its operation by a clutch having a driving surface 14 and a breaking surface 16, (Fig. 5) operating substantially as disclosed in the 30 patent just referred to. This machine operates to insert fastenings in succession, continuing or repeating the operation as long as its treadle is held depressed and its clutch in power transmitting condition.

35 A pulley 18 carried by a suitable stud shaft 20 mounted in the base of the column of the machine is continuously rotated from any suitable source of power such as a motor 22. Rotating with the pulley 18 is an eccentric 24, the strap 26 of which is connected by a link 28 to a pin 30 carried by a slide 32 mounted for reciprocation in ways carried by a bracket 34 secured to the base of the machine. Slide 32 is thus continuously 40 reciprocated and may conveniently be referred to as the live slide.

45 A second slide 36, normally stationary when the machine is at rest is also reciprocably mounted in ways carried by the bracket 34. Pivoted in an opening formed in slide 36 is a latch member 38 formed with a shoulder 40 which, when latch member 38 is moved into the position of Fig. 3, is engaged by a hardened block 42 carried by the live slide 32 so that slide 36 is raised with slide 32 from the position of Fig. 2 to the 50 position of Fig. 4. A spring 43 tends to move latch member 38 to the inoperative position of Fig. 2. The raising of slide 36 as will be more fully hereinafter described operates to raise the work support and to throw in the clutch to start the machine.

55 Pivoted at 44 to the lower end of slide 36 is a lever 46 fulcrumed at 48 on a block 50 mounted for limited sliding movement in

ways formed in bracket 34. A link 52 is connected at one end to lever 46 and at the other end to a cam bearing lever 54 fulcrumed on a pin 56 carried by the column of the machine. The end of lever 54 remote from link 52 is formed as a cam surface 58 co-operating with a roll 60 carried by part 62 of a two-part lever 62, 64 operative through toggle mechanism 66 to control the raising and the lowering of the horn when the machine is started and stopped as well as to release the horn for the feeding movement of the work as more fully described in United States Letters Patent No. 1,011,941.

The upper end of slide 36 is connected by a rod 70, having its upper end housed for limited longitudinal movement in a sleeve 71 (Fig. 5), to a lever 72 fulcrumed at 74 on the head of the machine and connected by a link 76 to a lever 78 forming part of the clutch operating mechanism already referred to. A spring 80 bearing at one end upon a lug 84 formed upon sleeve 71 and at the other against any suitable abutment such as a collar 86 carried by a rod 88 (hereinafter more fully described) tends to rock lever 72 in a counter-clockwise direction as viewed in Fig. 5. A suitable amount of lost motion is permitted between rod 70 and sleeve 71 so that when slide 36 is elevated the work support may be raised before lever 72 is rocked with the resulting throwing in of the clutch. Preferably this lost motion is so regulated that the clutch is thrown in just as or immediately after the work support reaches its highest position. On the other hand when the machine is stopped and slide 36 starts down under the control of latch mechanism hereinafter to be described, lever 72, under the influence of spring 80, follows rod 70 down so that the clutch will be moved to stopping position as soon as the machine reaches the appropriate point in its cycle of operation. The latch mechanism just referred to operates to prevent rod 70 from moving a sufficient distance to permit the lowering of the work support until after the clutch has been rendered inoperative and the machine stopped.

60 Fulcrumed at 100 to the base of the machine is a treadle 102 the rear of which is suitably connected as at 104, 106 to the above-mentioned rod 88 which is mounted for vertical sliding movement. A spring 112, more powerful than spring 80, bearing at one end against a collar 114 clamped upon rod 88 and at the other end against an abutment 116 carried by the column of the machine tends to depress rod 88 and to elevate treadle 102. The raising of rod 88 a small amount, which may be effected by the depression of treadle 102 a distance which may advantageously be less than an inch, results by mechanism now to be described, in the movement of latch member 38 from the position of Fig. 2 to the

position of Figs. 3 and 4 with the consequent starting of the machine.

A lever 120 clamped to a pin 122 having a bearing in bracket 34 is provided with an arm extended between a pair of collars 124, 126, clamped to rod 88 so that the elevation of the rod rocks the lever in a clockwise direction as viewed in Fig. 1, and with a second arm 130 arranged for engagement with a stop such as an adjustable screw 132 to limit the downward movement of rod 88. Also fast upon pin 122 is an arm 134 formed near its upper end with a shoulder 136 and carrying at its lower end a spring-pressed plunger 138 bearing against latch member 38 and in position to move it to the position of Fig. 3 when lever 120 is rocked by the raising of rod 88. Journaled upon pin 122 is a latch member 140 formed at its lower end with a shoulder-engaging surface 142 operative under different circumstances to engage either one of a pair of stepped shoulders 144, 146 formed upon slide 36. Near its upper end latch member 140 is formed with a projecting finger 148. A tension spring 150 anchored at one end to finger 148 and at the other end to a pin 152 carried by the lower end of arm 134 tends to hold finger 148 in engagement with the shoulder 136 of arm 134 and thus tends to rock latch member 140 in a clockwise direction as viewed in Figs. 1, 2, 3 and 4 when rod 88 is raised. Thus the depression of treadle 102 results in the movement of latch members 38 and 140 from the position of Fig. 2 to the position of Fig. 3, this taking place as soon after the depression of the treadle as slide 36 reaches its lowermost position. The engagement of shoulder 40 of latch member 38 above plate 42 results in the elevation of slide 36 as slide 32 moves upward, the lower end of latch member 140 being of such a shape as to permit that latch member to move against the tension of spring 150 as slide 36 is elevated so that as slide 36 reaches its uppermost position latch member 140 assumes the position shown in full lines in Fig. 4. Slide 36 is thus held in its raised position when slide 32 starts down and is so held during the insertion of fastenings or as long as treadle 102 remains depressed. As long as slide 36 is thus held in its elevated position the machine continues to operate to insert fastenings in the work carried by the work support, the latter being released however in the usual manner at the appropriate point in each cycle of operation of the machine to permit the feeding of the work.

Means which will now be described is provided for preventing rod 88 from moving, when treadle 102 is released, more than the short distance necessary to throw out the clutch until after the completion of the cycle of operation during which the treadle is released. This small movement of rod 88 is

not sufficient to permit any lowering movement of the work support so that it is thus insured that the last fastening will be completely driven. Connected at 160 to an extension 162 of the cam roll bearing lever of the clutch operating mechanism (Fig. 5) is a rod 164 surrounded by a spring 166 bearing at its lower end against a collar 168 clamped to the rod and at its other extremity against an abutment 170 carried by the frame of the machine. Rod 164, which is thus continuously reciprocated during the operation of the machine by the co-operative action of the clutch cam 171 and cam roll 173, is connected at its lower end to a bell crank lever 172 fulcrumed on bracket 34 and having pivoted to its upper extremity a finger 174 carrying at its outer end an adjustable bearing screw 176 having a rounded end engaging a finger 178 extending from collar 126 (Figs. 1 and 2). A tension spring 180 anchored at one end to finger 174 and at the other end to a pin extending from lever 172 serves to hold the lower end of screw 176 in sliding engagement with finger 178 as bell crank lever 172 is rocked by the reciprocation of rod 164. A notch 182 is formed in the upper extremity of latch member 140. While the machine is running the elevated position of finger 178 serves to lift finger 174 and thus holds the extremity of finger 174 above the upper end of latch member 140. When treadle 102 is released and rod 88 is lowered latch member 140 is moved from the full line to the dotted line position of Fig. 4. This permits slide 36 to move down only a short distance, until shoulder 146 formed thereon engages surface 142 of the latch member. This permits sufficient movement of rod 70 to permit the throwing out of the clutch but is insufficient to permit any lowering of the work support. Thereafter, and at substantially the same instant as the throwing out of the clutch, rod 164 is elevated by the counter clockwise movement (as viewed in Fig. 5) of lever arm 162. Since prior to this time finger 178 has moved down from the position of Fig. 3, the extremity of finger 174 is permitted to engage notch 182 of latch member 140. The subsequent upward movement of rod 164 and the corresponding movement of finger 174 to the left as viewed in Figs. 2 to 4 result in rocking latch member 140 from the dotted line position of Fig. 4 to the position of Fig. 2. Slide 36 is thus released and moves to its lowermost position.

It may occasionally be desired to raise slide 36 manually. For example in making certain adjustments it may be necessary or convenient to raise the work support without throwing in the clutch and starting the operation of the machine. Accordingly a second treadle 190 is provided, the rear end of which is connected through a rod 192

and a spring 194 with a sleeve 196, the upper extremity of which bears against the lower end of slide 36. By means of treadle 190 slide 36 may be elevated a sufficient distance 5 to raise the work support to operative position without throwing in the clutch; or if treadle 190 is depressed through its entire throw the work support may be raised and the clutch thrown in to cause the insertion 10 of fastenings, this being at times advantageous if it is desired to insert a single, accurately located fastening. It may be noted that when the machine is operated under the control of treadle 102 and the power-operated work support and clutch controlling mechanism, sleeve 196 and spring 194 act 15 as a buffer to cushion the fall of slide 36.

Having described my invention, what I 20 claim as new and desire to secure by Letters Patent of the United States is:

1. A machine arranged, when started, to operate continuously and thereby to perform an operation a plurality of times in rapid succession having, in combination, cyclically 25 operating mechanism, a work support, a clutch for transmitting power to cause operation of said mechanism, and power-operated means for raising the work support prior to the starting of said mechanism and 30 for throwing in said clutch.

2. In a machine of the class described, a work support, a clutch for controlling the operation of the machine, and operator-controlled, continuously running, power-operated 35 means for raising the work support and throwing in the clutch.

3. In a machine of the class described, a work support, a clutch for controlling the operation of the machine, continuously running, power-operated cyclically operating 40 means operable at a predetermined time in its cycle of operations for raising the work support and throwing in the clutch, and controlling means operable at any time in the 45 cycle of operations of said power-operated means for causing the power-operated means at a predetermined time in its cycle of operations to operate to raise the work support and throw in the clutch.

4. In a machine of the class described, a work support, a clutch for controlling the operation of the machine, connections between the work support and the clutch, and power-operated means operable on said 55 connections to raise the work support and throw in the clutch and to maintain the clutch in power-transmitting condition through a plurality of cycles of operation.

5. In a machine of the class described, a work support, a clutch for controlling the operation of the machine, connections between the work support and the clutch, power-operated means operable on said 60 connections to raise the work support and throw

in the clutch and to maintain the clutch in 65 power-transmitting condition through a plurality of cycles of operation of the machine, and means for controlling the movement of said connections in a direction to lower the work support and throw out the clutch. 70

6. In a machine of the class described, a work support, a clutch for controlling the operation of the machine, connections between the work support and clutch, power-operated means operable on said connections to raise the work support and throw in the clutch, and operator-controlled and machine-controlled means for controlling the movement of said connections in a direction to lower the work support and throw out 80 the clutch.

7. In a machine of the class described, a work support, a clutch for controlling the operation of the machine, a slide connected to the work support and clutch, and power-operated means for operating said slide to raise the work support and throw in the clutch. 85

8. In a machine of the class described, a work support, a clutch operable when thrown in to cause repeated operation of the machine, connections between the work support and clutch, normally-inoperative power-operated means for operating on said connections to raise the work support and throw in the clutch, and operator-controlled means for rendering said power-operated means operative on said connections. 90

9. In a machine of the class described, a work support, a clutch for controlling the 100 operation of the machine, connections between the work support and clutch, normally-inoperative power-operated means for operating on said connections to raise the work support and throw in the clutch, a member operatively associated with said connections and arranged to be interposed in the path of movement of the power-operated means to render said means operative on 105 said connections, and operator-controlled means for interposing said member into the path of movement of the power-operated means. 110

10. In a machine of the class described, a work support, a clutch for controlling the operation of the machine, connections between the work support and clutch, power-operated means for operating said connections so as to raise the work support and throw in the clutch, and means for retaining the connections in a position to maintain the work support in raised position and the clutch thrown in. 115

11. In a machine of the class described, a work support, a clutch for controlling the operations of the machine, connections between the work support and clutch, normally-inoperative power-operated means for 120 125

operating on said connections to raise the work support and throw in the clutch, operator-controlled means for rendering said power-operated means operative on said connections, means co-acting with said connections to maintain the clutch thrown in and the work support raised, and means operated by said operator-controlled means for rendering said maintaining means inoperative

10 on said connections.

12. In a machine of the class described, a work support, a clutch for controlling the operation of the machine, connections between the work support and clutch, normally-inoperative power-operated means for operating on said connections to raise the work support and throw in the clutch, a member operatively associated with said connections and arranged to be interposed in

15 the path of movement of the power-operated means, a shaft disposed adjacent to said connections, mechanism carried by said shaft and operable to interpose said member into the path of movement of the power-operated

20 means to render said means operative on said connections, means for retaining the connections in position to maintain the work support raised and the clutch thrown in, and means for disengaging said retaining means

25 from said connections upon movement of said mechanism away from said member.

13. In a machine of the class described, a work support, a clutch for controlling the operation of the machine, connections between the work support and clutch, normally-inoperative power-operated means for operating said connections to raise the work support and throw in the clutch, a member operatively associated with said connections

30 and arranged to be interposed in the path of movement of the power-operated means to render said means operative on said connections, a shaft disposed adjacent to said connections, mechanism carried by said shaft

35 and operable to interpose said member into the path of movement of the power-operated means so as to cause said connections to be operated, means carried by the shaft for retaining the connections in position to

40 maintain the work support raised and the clutch thrown in, means for moving said mechanism away from said member to permit said member to pass out of the path of movement of said power-operated means

45 and for withdrawing said retaining means for engagement with said connections, and means on said shaft arranged to arrest the connections after movement thereof sufficient to throw out the clutch, said connections being constructed to maintain the work support in raised position during such movement of the connections.

14. In a machine of the class described, a work support, a clutch for controlling the

operation of the machine, connections between the work support and clutch, means operatively connected with such connections for maintaining the work support in raised position and the clutch thrown in through a plurality of cycles of operation of the machine, and means for rendering said maintaining means inoperative on said connections.

15. In a machine of the class described, a work support, a clutch for controlling the operation of the machine, connections between the work support and clutch, means operatively associated with such connections for maintaining the work support in raised position and the clutch thrown in, and operator-controlled means for rendering said maintaining means inoperative on said connections.

16. In a machine of the class described, a work support, a clutch for controlling the operation of the machine, connections between the work support and clutch, shoulders on said connections, means arranged for engagement with one of said shoulders to maintain the connections in position with the work support raised and the clutch thrown in, and means to engage the other of said shoulders to maintain said connections in a different position.

17. In a machine of the class described, a work support, a clutch for controlling the operation of the machine, a slide connected to the work support and clutch, shoulders on said slide, means arranged for engagement with one of said shoulders to retain the slide in position with the work support raised and the clutch thrown in, connections between the slide and work support constructed to maintain the work support in raised position upon movement of the slide to a position to cause the clutch to be thrown out and means operatively connected with said first-mentioned retaining means and arranged for engagement with the other of said shoulders to retain the slide in such last-named position.

18. In a machine of the class described, a work support, a clutch for controlling the operation of the machine, a slide connected to the work support and clutch, shoulders on said slide, means arranged for engagement with one of said shoulders to maintain the slide in position with the work support raised and the clutch thrown in, connections between the slide and work support constructed to maintain the work support in raised position upon movement of the slide to a position to cause the clutch to be thrown out, means operatively connected with said maintaining means and arranged for engagement with the other of said shoulders to retain the slide in such last-named position, and means operated sub-

stantially simultaneously with the throwing out of the clutch for releasing said last-mentioned maintaining means to permit lowering of the work support upon the stopping 5 of the machine.

19. In a machine of the class described, a work support, a clutch for controlling the operation of the machine, connections between the work support and clutch, means 10 co-acting with said connections operable to maintain the clutch thrown in and the work support in raised position through a plurality of cycles of operation of the machine, means for releasing said maintaining means, 15 means co-acting with said connections to maintain the same in a position to cause the clutch to be thrown out and the work support to continue in raised position, and means for releasing said last-named maintaining 20 means to permit the work support to be lowered substantially simultaneously with the stopping of the machine.

20. In a machine of the class described, a frame, a constantly rotating shaft carried by said frame, a member movably mounted on said frame and operated by said shaft, a work support, mechanism operatively connected to the work support and comprising an element positioned normally out of the 25 path of movement of said member, means for moving said element into the path of movement of said member to cause the work support to be raised by said member, and means separate from said mechanism for lowering the work support periodically to 30 permit the work to be fed.

21. In a machine of the class described, a frame, a constantly rotating shaft carried by said frame, a member movably mounted 40 on said frame and operated by said shaft, a work support, mechanism connected to the work support comprising an element positioned normally out of the path of movement of said member, treadle-controlled means for moving said element into the path of movement of said member to cause the work support to be raised by said member, and means operatively connected with the treadle-controlled means for maintaining 45 the work support in raised position.

22. In a machine of the class described, a frame, a constantly rotating shaft carried by said frame, a member movably mounted on said frame and operated by said shaft, a work support, mechanism connected to the work support comprising an element positioned normally out of the path of movement of said member, means carried by the frame in position when operated to shift 55 said element into the path of movement of said member, operating means for said shifting means movable by the operator in opposite directions between two limits of movement, and mechanism for maintaining 60 the work support in raised position when

said operating means is at the limit of its movement in either direction.

23. In a machine of the class described, a frame, a constantly rotating shaft carried by said frame, a member movably mounted 70 on said frame and operated by said shaft, a work support, a slide connected to the work support and mounted in said frame, an element carried by said slide positioned normally out of the path of movement of 75 said member, mechanism on said frame arranged for engagement with said element when the slide is in position to lower the work support, means for operating said mechanism to interpose said element into the path of movement of said member so that said member operates to raise the work support, means operatively connected to 80 said operating means for maintaining the work support in raised position, and means for automatically rendering the work support maintaining means inoperative.

24. In a machine of the class described, a frame, a constantly rotating shaft carried by said frame, a member movably mounted 90 on said frame and operated by said shaft, a work support, a slide connected to the work support and mounted in said frame, an element carried by said slide positioned normally out of the path of movement of 95 said member, a shaft, a bell crank lever carried by said shaft and having a depending portion arranged for engagement with said element when the slide is in position to lower the work support, operator-controlled means for operating said lever to interpose 100 said element into the path of movement of said member to initiate the raising of the work support, and an arm mounted on said shaft constructed for locking engagement with said slide to maintain the work support in raised position.

25. In a machine of the class described, a frame, a constantly rotating shaft carried by said frame, a member movably mounted on said frame and operated by said shaft, a work support, a slide connected to the work support and mounted in said frame, an element carried by said slide positioned normally out of the path of movement of 110 said member, a shaft, a bell crank lever carried by said shaft and having a depending portion arranged for engagement with said element when the slide is in position to lower the work support, operator-controlled means for operating said lever to interpose 115 said element into the path of movement of said member to initiate the raising of the work support, an arm mounted on said shaft constructed for locking engagement with said slide to maintain the work support in raised position, and a yielding connection 120 between said bell crank lever and said arm arranged to move said arm into locking engagement with said slide upon actuation of 125

the bell crank to effect raising of the work support.

26. In a cyclically operating machine, a work support, power-operated means for raising the work support, means operable to maintain the work support in raised position during a plurality of cycles of operation of the machine, clutch mechanism for controlling the operation of the machine, and means operated by the clutch mechanism for releasing the work support maintaining means to permit the work support to be lowered.

27. In a machine of the class described, in combination, a work support, a clutch comprising a movable clutch member, work support controlling means, clutch controlling means, means for operating said clutch member, connections between said clutch controlling means and said work support controlling means, means co-acting with said connections operable to maintain the work support in raised position during a plurality of cycles of operation of the machine, and means operated by said clutch member operating means for releasing said maintaining means to permit lowering of the work support.

28. In a machine of the class described, in combination, a work support, a clutch comprising a movable clutch member, work support controlling means, clutch controlling means, means for operating said clutch member, connections between said clutch controlling means and said work support controlling means, means co-acting with said connections for maintaining the work support in raised position and the clutch thrown in, means for rendering said maintaining means inoperative on said connections, means for limiting the movement of said connections to a point to cause said clutch controlling means operatively to connect said clutch member with said clutch member operating means while continuing to maintain the work support in raised position, and means operated by said clutch member operating means for rendering said limiting means inoperative substantially simultaneously with the throwing out of the clutch member by said clutch member operating means to permit the work support to be lowered when the machine is stopped.

29. In a machine of the class described, a work support, clutch mechanism for controlling the operation of the machine constructed to stop the machine at a predetermined point in the cycle of operations of the machine and comprising clutch controlling means operable at any time in the cycle of operations of the machine to cause the machine to stop at such predetermined point of its operation, a work support, a member connected to said clutch-controlling means and said work support, manually controlled means for maintaining said member in a

position to maintain the work support in raised position and to throw in the clutch, means for latching said member when released by said manually controlled maintaining means in a position to operate the clutch controlling means, means controlled by said clutch for releasing said member from said latching means to permit movement of said member from latching position, and connections between said member and the work support constructed to maintain the work support in raised position regardless of the movement of said member from said first-mentioned position to said second-mentioned position and to lower the work support upon further movement of said member subsequent to the release of said member from the control of the latching means.

30. In a machine of the class described, a clutch for controlling the operation of the machine, power-operated means for throwing in the clutch, means for disconnecting the clutch from the power-operated means, and means independent of the first-named power operated means and operated by the power of the machine for throwing out the clutch at a predetermined time in the cycle of operations of the machine to stop the machine.

31. In a machine of the class described, a clutch for controlling the operation of the machine, power-operated means for throwing in the clutch, operator-controlled means for rendering the power-operated means operative on the clutch, and means operatively connected with the operator-controlled means for maintaining the clutch thrown in.

32. In a machine of the class described, a clutch for controlling the operation of the machine, a slide connected to said clutch, power-operated means for operating said slide, and treadle-controlled means for operatively connecting said slide and said power-operated means.

33. In a machine of the class described, means for operating repeatedly on shoe stock, means for controlling the shoe stock in the field of operation of the operating means during repeated operations on the stock, a clutch for controlling the operating means, and power-operated means for actuating the stock controlling means and for throwing in the clutch to cause the machine to operate repeatedly on the stock.

34. In a machine of the class described, means for operating repeatedly on shoe stock, means for clamping the shoe stock, a clutch for controlling the operating means, and power-operated means for actuating the clamping means and throwing in the clutch to cause the operating means to operate repeatedly on the stock.

35. In a machine of the class described, means for inserting fastenings successively

- into shoe stock, a clutch for controlling the fastening inserting means, mechanism operable on the shoe stock to facilitate the insertion of fastenings into the shoe stock, and power-operated means for actuating said mechanism and throwing in the clutch to cause the successive insertion of fastenings. 5
36. In a machine of the class described, clutch mechanism constructed to stop the machine at a predetermined time in the cycle of operations of the machine, a work support, power-operated means for raising the work support and throwing in the clutch, operator-controlled means for rendering the power-operated means inoperative on the work support and clutch mechanism and for initiating the operation of the clutch mechanism to stop the machine, and means operated by the clutch mechanism to lower the work support substantially simultaneously with the stopping of the machine. 10
37. In a machine of the class described, a work support, a clutch for controlling the operation of the machine, power-operated means operable at a predetermined point in the cycle of operations of the machine for raising the work support and throwing in the clutch or for throwing out the clutch and lowering the work support, and controlling means operable at any time during the operation of the machine for causing operation of the power operated means to throw out the clutch and lower the work support at such predetermined point in the cycle of operations of the machine. 15
38. In a machine of the class described, a work support, a clutch for controlling the operation of the machine, and a power-operated eccentric for raising the work support and throwing in the clutch. 20
39. In a machine of the class described, a work support, a clutch for controlling the operation of the machine, a power driven eccentric for raising the work support and throwing in the clutch, a treadle operable at any time during the operation of the machine to stop the machine, and connections from the treadle to the clutch and work support for causing the throwing out of the clutch and the lowering of the work support at a predetermined point in the cycle of operations of the machine. 25
40. In a machine of the class described, a work support, a clutch for controlling the operation of the machine, a slide connected to the work support and clutch, and a power operated eccentric for operating the slide to raise the work support and throw in the clutch. 30
41. A metallic fastening inserting machine having, in combination, a work support, a continuously driven eccentric for raising said work support, and a latch arranged to hold the work support in raised position. 35
42. A metallic fastening inserting machine having, in combination, a work support, a continuously driven eccentric, a slide continuously moved thereby, and connections from said slide to said work support operable under the control of the operative to cause said slide to raise said work support. 70
43. A metallic fastening inserting machine having, in combination, a work support, a power operated, continuously reciprocated slide, a normally stationary slide adjacent thereto, connections from said normally stationary slide to said work support, and a latch operable under the control of the operative for causing said continuously reciprocated slide to move said normally stationary slide and through said connections to raise said work support. 75
44. A metallic fastening inserting machine having, in combination, a work support, a clutch, and power operated means for raising the work support and for throwing in the clutch in timed relation thereto to cause the machine to operate through a plurality of cycles of operation. 80
45. In a machine of the class described, a continuously driven slide, a normally stationary slide, a latch operable under the control of the operative to connect said slides thereby to cause the continuously driven slide to move the normally stationary slide, a second latch arranged to act subsequent to said first-named latch to retain said normally stationary slide in the position to which it has been moved by said first-named latch, and a work support under the control of said normally stationary slide. 85
46. In a machine of the class described, a clutch, a work support, power operated means for raising the work support, a latch operable to retain said work support in raised position, a treadle, and connections from the treadle to the clutch and to the work support arranged to throw out the clutch, after movement of the treadle to stop the machine, at a predetermined point in the cycle of operations of the machine and thereafter to lower the work support. 90
47. A machine of the class described having, in combination, a work support, a clutch for controlling the operation of the machine, power-operated means for raising the support and throwing in the clutch, and a member arranged when in one position to maintain the clutch and the work support in operative position and when in another position to permit the release of the clutch but still to maintain the work support in operative position. 115
48. A machine of the class described, having, in combination, a work support, a clutch for controlling the operation of the machine, a slide connected to the work support and clutch, power-operated means for moving the work support. 120
49. A machine of the class described, having, in combination, a work support, a clutch for controlling the operation of the machine, a slide connected to the work support and clutch, power-operated means for moving the work support. 125
50. A machine of the class described, having, in combination, a work support, a clutch for controlling the operation of the machine, a slide connected to the work support and clutch, power-operated means for moving the work support. 130

the slide to raise the work support and throw in the clutch, and a latch member arranged when in one position to hold the slide in position to maintain the work support and the clutch in operative position and when in another position to maintain the work support in operative position but to permit the release of the clutch.

49. A machine of the class described having, in combination, a work support, a movable slide arranged when in one position to maintain the work support in operative position and to cause operation of the machine and when in another position to maintain the work support in operative position and to permit the stopping of the machine, and a latch member under the control of the operative and arranged to hold said slide in either of said two positions.

50. A machine of the class described having, in combination, a work support, a clutch for controlling the operation of the machine, power-operated means operable at a predetermined point in the cycle of operation of the machine to raise the work support and throw in the clutch and operable also to stop the machine, and a member under the control of the operative for causing said power-operated means, when operated to stop the machine, first to throw out the clutch and thereafter to lower the work support.

51. A machine of the class described having, in combination, a work support, a clutch, a latch member, and connections from the latch member to the work support and clutch, the latch member having three positions in one of which it maintains the clutch and work support in operative position, in a second of which it maintains the work support in operative position, and in the third of which it maintains neither the clutch nor the work support in operative position.

52. A machine of the class described having, in combination, a work support, a clutch for controlling the operation of the machine, a slide, connections from the slide to the clutch arranged, when the slide is brought into operative position, to cause the throwing in of the clutch, a lever pivoted to the slide and rocked by the movement of the slide to operative position, and connections from the lever to the work support arranged to move the work support into operative position prior to the throwing in of the clutch.

53. A machine of the class described having, in combination, a continuously power-reciprocated slide, a second slide arranged to control the operation of the machine, a latch, a controller, connections from the controller to the latch arranged to cause movement of the controller to shift the latch so as to cause the continuously reciprocated slide to move the second slide into position to

cause the operation of the machine, and a latch member operative to maintain said second slide in position to cause the continued operation of the machine and movable, upon the return of the controller to its normal position first, to an extent to permit said second slide to move only part of the distance from operative to inoperative position, and after a short dwell to permit said second slide to move to inoperative position.

54. A machine of the class described having, in combination, fastening inserting means, a clutch for controlling the operation thereof, a work support, a slide, power-operated means for moving the slide into position to throw in the clutch and raise the work support, a latch member arranged to maintain the slide in said position, and means operable to withdraw the latch member to an extent sufficient to permit the throwing out of the clutch and insufficient to permit the lowering of the work support.

55. A machine of the class described having, in combination, fastening inserting means, a clutch for controlling the operation thereof, a work support, a slide, power-operated means for moving the slide into position to throw in the clutch and raise the work support, a latch member arranged to maintain the slide in said position, means operable to withdraw the latch member to an extent sufficient to permit the throwing out of the clutch and insufficient to permit the lowering of the work support, and means for thereafter moving the latch member into position to permit the lowering of the work support.

56. A machine of the class described having, in combination, a clutch arranged to control the operation of the machine, a slide having a pair of latch engaging surfaces, a latch member arranged to engage one of said surfaces during the operation of the machine and to engage the other of said surfaces when the machine is to be stopped to permit the throwing out of the clutch prior to the movement of other parts of the machine to their normal inoperative position.

57. A machine of the class described having, in combination, a work support, fastening inserting instrumentalities, a clutch for controlling the operation thereof, a cam, connections from the cam to the clutch, means for breaking and making said connections to cause the throwing in and out of the clutch, a latch arranged to maintain said connection breaking and making means in position to hold said connections broken and arranged when in another position to permit the making of said connections to cause the cam to move the clutch into inoperative position while at the same time holding the work support raised, and means operated by said cam to move the latch to inoperative position.

position coincident with the throwing out of the clutch to permit the lowering of the work support.

58. A fastening inserting machine having, in combination, a work support, fastening inserting instrumentalities, means for raising the work support into operative relation to said fastening inserting instrumentalities comprising a slide, a lever pivoted to said slide, and connections from the lever to the work support whereby movement of the slide is transmitted through the lever to the connections to cause the raising and lowering of the work support.
59. A fastening inserting machine having, in combination, a work support, fastening inserting instrumentalities, means for raising the work support into operative relation to said fastening inserting instrumentalities comprising a slide, a lever connected to said slide, and connections from the lever to the work support whereby movement of the slide is transmitted through the lever to the connections to cause the raising and lowering of the work support.

60. A machine of the class described having, in combination, a continuously driven slide, a normally stationary slide a latch operable under the control of the operative to connect said slides thereby to cause the continuously driven slide to move the normally stationary slide, a second latch arranged to act subsequently to the first named latch to retain said normally stationary slide in the position to which it has been moved by said first named latch, a clutch and a work support under the control of said normally stationary slide, means operable to cause said first-named latch to disconnect the two slides and at the same time to cause said second-named latch to allow movement of the normally stationary slide to an extent sufficient to permit the throwing out of the clutch but insufficient to permit the lowering of the work support, and means operative synchronously with the throwing out of the clutch completely to withdraw said second-named latch from the normally stationary slide so as to permit the normally stationary slide to move into position to cause the lowering of the work support.

61. A machine of the class described having in combination, a clutch, a work support, a latch having two operative positions in both of which it holds said work support in raised positions and in one of which it maintains the clutch in operative condition, a treadle, and connections from the treadle to the clutch and to the work support arranged to cause movement of the latch, after movement of the treadle to stop the machine, to permit the throwing out of the clutch without lowering of the work support at a predetermined point in the

cycle of operation of the machine and thereafter to move the latch into position to permit lowering of the work support.

62. A machine of the class described having, in combination, a clutch, a work support, and a latch having two operative positions in both of which it holds said work support in raised position and in one of which it maintains the clutch in operative condition.

63. A slide for controlling the operation of a machine, provided with a pair of latch engaging surfaces by the engagement of which the slide may be held in either one of two definite positions.

64. A machine of the class described having, in combination, a slide, means for moving the slide to a definite position to cause the continued operation of the machine, and a latch member, the slide being formed with two surfaces arranged for engagement by the latch member to maintain the slide in said definite position or to permit its movement therefrom while restraining it from movement to its normal inoperative position.

65. In a machine for operating on shoe stock, a constantly reciprocating slide serving as a source of power for the machine, a second slide adapted to be connected to the first mentioned slide, and means under the control of the operator for causing the slides to be operatively connected.

66. In a machine for operating on shoe stock, a constantly reciprocable slide serving as an immediate source of power for the machine, a second slide adapted to be operatively connected to the first-mentioned slide so as to be moved thereby to a predetermined operative position, means for locking the second slide in said operative position, and means under the control of the operator for causing the operative connection of the slides and for releasing the second slide from the locking means.

67. In a machine for operating on shoe stock, a constantly reciprocable slide, power means for reciprocating the slide while the machine otherwise is at rest, a second slide adapted to be operatively connected to the first slide, a manually operable member for causing operative connection between the slides, a member for locking the second slide in the extreme position to which it is moved by the first slide, said second slide having two abutments with one of which the locking member may co-operate to lock the slide at the extreme limit of its movement in one direction, the other abutment serving to lock the slide slightly retracted from its extreme position, and connections controlled from the manually operable member for causing unlocking of the second slide from its extreme position and its retention in the slightly retracted position.

68. In a machine for inserting fastenings in shoe stock while the latter is clamped temporarily during the insertion of each fastening, a constantly reciprocable slide serving as an immediate source of power for the machine, a second slide adapted to be operatively connected to the first-mentioned slide to be moved thereby to the position it occupies while the stock is clamped for the insertion of fastenings, a locking member for holding the second slide in its operative position while the first-mentioned slide continues to reciprocate, and a manually operable member for causing operative connection between the slides and for releasing the second slide from its extreme operative position when it is desired to terminate the clamping of the stock. 65
69. In a machine for inserting fastenings in shoe stock, a constantly reciprocable slide, a second slide adapted to be operatively connected to the first-mentioned slide to be moved thereby to the extreme limit of its movement in one direction, locking means for holding the second slide at the said limit of its movement during all of the time of the insertion of the fastenings, a manually operable member for releasing the second slide from its extreme position to an intermediate position determined by the locking means, and power means for releasing the slide from said intermediate position at a predetermined point in the cycle of operations. 70
70. In a machine for operating on shoe stock, a constantly reciprocable slide serving to transmit power to the machine, a second slide adapted to be operatively connected to the first-mentioned slide so as to be moved thereby to a predetermined operative position, means for locking the second slide in said operative position during continued reciprocations of the first slide, and means under the control of the operator for releasing the second slide from the locking means. 75
71. In a machine for operating on shoe stock, a constantly reciprocable slide, power means for reciprocating the slide while the machine otherwise is at rest, a second slide adapted to be operatively connected to the first slide, a manually operable member for causing operative connection between the slides, a member for locking the second slide in the extreme position to which it is moved by the first slide, said second slide having a plurality of abutments with which the locking member may co-operate to lock the slide selectively in a number of positions, one abutment serving to lock the slide slightly retracted from its extreme position, and connections controlled from the manually operable member for causing unlocking of the second slide so that it may return to its initial position occupied while the machine is at rest. 80
72. In a machine for inserting fastenings in shoe stock, a constantly reciprocable slide, a second slide adapted to be operatively connected to the first-mentioned slide to be moved thereby to the extreme limit of its movement in one direction, a locking means for holding the second slide at the said limit of its movement during all of the time of the insertion of the fastenings, a manually operable member for initiating the release of the second slide from its extreme operative position, and power means for releasing the slide at a predetermined point in the cycle of operations. 85
73. In a machine of the class described, a work support, a clutch for controlling the operation of the machine, connections between the work support and the clutch, power-operated means for operating said connections to raise the work support and throw in the clutch, a manually operated controller displaceable to render said power-operated means operative upon said connections, and means for retaining the connections in a position to maintain the work support in raised position and the clutch thrown in as long as said controller is maintained in displaced position. 90
74. A fastening-inserting machine operating step by step to insert a plurality of fastenings in succession having, in combination, a work support, a continuously driven eccentric operable to raise the work support preliminarily to the insertion of a group of fastenings, and a latch operable to hold the work support in raised position through a plurality of cycles of operation of the machine during the successive insertion of fastenings. 95
75. A cyclically operating fastening-inserting machine operable to insert fastenings successively having, in combination, a work support, a clutch, power-operated means for raising the work support preliminarily to the insertion of a plurality of fastenings and for throwing in the clutch in timed relation thereto, a manually displaceable controller arranged operatively to connect the power-operated means and the means for raising the work support and for throwing in the clutch, and means for holding the work support in raised position and the clutch in power-transmitting condition as long as the controller is maintained in displaced position. 100
- In testimony whereof I have signed my name to this specification.
- FRED L. MACKENZIE.
